United States Patent Office.

ISAAC DRIPPS, OF FORT WAYNE, INDIANA.

Letters Patent No. 78,074, dated May 19, 1868.

RAILWAY-CAR STOVE.

The Schedule referred to in these Letters Patent and making part of the same.

TO ALL WHOM IT MAY CONCERN:

Be it known that I, ISAAC DRIPPS, of Fort Wayne, in the county of Allen, and State of Indiana, have invented a new and useful Improvement in Stoves especially adapted for use in Railway-Cars; and I do hereby declare that the following is a full, clear, and exact description of the same, reference being made to the annexed drawings, making part of this specification, in which—

Figure 1 is a front elevation of the stove, showing the casing in section.

Figure 2 is a vertical section through the line A B, fig. 1.

Figure 3 is a front elevation of the stove and casing complete.

Figure 4 is a plan of the bottom part of the stove.

Figure 5 is a horizontal half section through the line c d, fig. 2, and half section through a b.

Figure 6 is a plan showing the door and door-frame.

Figure 7 is an elevation of the door and frame, showing the door open.

The same letters are employed in all the figures in the indication of the same parts.

My invention relates to a stove or heater particularly designed for railway-cars, and having an external case through which a current of air passes around over the stove, which, being heated, is discharged into the car; and it consists in the arrangement of parts, to be hereinafter described, for securing the proper heating of the current of air, and also providing against the danger of setting fire to the car in case of an accident resulting in overturning the stove.

In the annexed drawings, W is the stove-cylinder, into which the fuel may be introduced through the door K. In the bottom of the cylinder is the grate U, on which the coals rest. A hole, S, in the lower part of the stove, is intended for the insertion of a poker. The smoke passes out through a pipe leading from the top of the stove.

The stove rests upon the ash-box H, in which is a drawer to catch the ashes. The ash-box rests upon a diaphragm, d d, placed across the base, D, to which the other parts are fastened, all the parts described being made strong enough to support the stove even in a horizontal position, and to resist the shock attending the overturning of the car. The base, D, is strongly bolted to the floor of the car.

C is a casing of heavy sheet iron surrounding the stove, extending upwards from the base, D, to the top of the stove, being covered by a cast-iron top plate, E, through the centre of which the pipe passes. This case is secured to the base by rods I I passing through the top plate, and also through lugs in the base. The casing is divided into two compartments by partitions B B' extending upward from the diaphragm in the base to the top of the stove, so that a current of air entering upon one side of the base, D', must flow upwards, and, passing over the stove, descend on the other side, to escape through an opening on the opposite side, D'', of the base from that on which it entered.

In order to increase the heating-surface of the stove, I propose to place pipes, F F, across the upper part of the stove, opening through the shell into the compartments on opposite sides of the partitions, through which the current of air, passing around and over the stove, may flow.

The opening into the ash-box is closed by a door, H'. Another door, M', closes the opening M, through which the draught is admitted. The bottom of the opening M is formed by a fine grating, O, so that in case of accident, coals falling into the ash-box could not fall out through the door M' into the car. K is the fire-door, through which the fuel may be introduced into the stove. As the greatest number of accidents occur by the bursting open of the stove-doors and the discharge of the burning coals into the wreck of a broken car, especial care is required properly to secure this door. This may be done by locking the doors M' in the usual manner.

The door H' should be secured in the same manner, as coals might otherwise fall through it to set fire to the car. Over the firing-door K is another ventilating-door, N, for aiding in the regulation of the draught, as air may be introduced through this door into the top of the stove over the fire. To prevent the escape of coals small holes are drilled through the cylinder opposite this door. The space between the several doors and the

stove-cylinder is surrounded by plates, which prevent the escape of air from the compartments within the casing. In order to prevent coals escaping through the stove-pipe hole, in case the stove should be overturned, I place a perforated diaphragm, R, across the stove near the top, the openings in which, while they allow a free circulation, are too small to permit the escape of coals.

What I claim as my invention, and desire to secure by Letters Patent, is—

1. The grating O, placed in the bottom of the draught-opening M, and over the ash-box, substantially as and for the purpose set forth.
2. The arrangement of the perforations P and door N, substantially as and for the purpose set forth.
3. A stove constructed with the grating O, perforations P, and perforated diaphragm R, arranged substantially as and for the purpose set forth.

ISAAC DRIPPS.
